UNITED STATES PATENT OFFICE.

FRANK B. GRISWOLD, OF TROY, NEW YORK.

DESIGN FOR A BAND-TIGHTENER FOR TIRES.

SPECIFICATION forming part of Design No. 27,305, dated July 6, 1897.

Application filed March 10, 1897. Serial No. 626,889. Term of patent 7 years.

To all whom it may concern:

Be it known that I, FRANK B. GRISWOLD, of Troy, Rensselaer county, New York, have invented and produced a new and original 5 Design for Band - Tighteners for Vehicle-Tires, of which the following is a specification.

The device to which my design relates is a tightener which consists of two parallel plates of metal, separated, but joined over a part of 10 their circumference, from one of which plates extends a cylindrical rod.

My design consists in the configuration of said tightener, as illustrated in the drawings, of which—

15 Figures 1 and 2 are side elevations taken from points of view ninety degrees apart, and Fig. 3 a plan view.

Similar letters of reference indicate like parts.

20 My design shows a cylindrical body A, ex-

tending from and concentric with a circular plate B. Parallel to the plate B is another circular plate C. Between the plates B and C is an arc-shaped wall D, which appears integrally with the said plates. Between plates 25 B and C is a recess or opening E. The plate C may appear beveled on its outer side, as shown in Fig. 1, and the cylindrical body A may have apertures, as F and G; but the presence of these apertures and the beveling 30 of the plate C are not essential features of my design and may be omitted.

I claim—

The design for a band-tightener for vehicle-tires, substantially as shown and described. 35

FRANK B. GRISWOLD.
